UNITED STATES PATENT OFFICE.

FREDERICK A. PHELPS, OF NEWARK, NEW JERSEY, ASSIGNOR TO TAYLOR IRON & STEEL COMPANY, OF HIGH BRIDGE, NEW JERSEY, A CORPORATION OF NEW JERSEY.

MACHINE FOR GRINDING TEETH OF GEAR-WHEELS.

No. 903,106.

Specification of Letters Patent.

Patented Nov. 3, 1908.

Application filed May 3, 1906. Serial No. 314,926.

To all whom it may concern:

Be it known that I, FREDERICK A. PHELPS, a citizen of the United States, residing in Newark, New Jersey, have invented a certain new and useful Improvement in Machines for Grinding Teeth of Gear-Wheels, of which the following is a specification.

This invention relates to improvements in machines for grinding gears having involute or other shaped teeth, and particularly is of use for grinding gears of very hard material.

The objects of the invention are to render it possible to grind teeth of wheels made of exceedingly hard material, to make the operation take as little time as possible, and to render it possible to grind teeth of the true involute shape desired. Other improvements reside in the shape of the grinder used, which permits finer teeth being ground, and also gives a longer life to the grinder.

I attain these objects by the mechanism illustrated in the accompanying drawings, which show one embodiment of the invention, and in which

Fig. 1 is a top view of a grinding machine showing a wheel in position, with the grinders in their inmost position; Fig. 2 is a similar view showing the grinders in their outermost position; Fig. 3 is a side view of the machine shown in Figs. 1 and 2; Fig. 4 is a vertical section thereof taken on the lines 4—4 of Fig. 2; Fig. 5 is a section on the lines 5—5 of Fig. 3; Fig. 6 is a section on the lines 6—6 of Fig. 3; Fig. 7 is a section on the lines 7—7 of Fig. 5; Fig. 8 is a section on the lines 8—8 of Fig. 4; Fig. 9 is a detail on a large scale of the portion of the mechanism shown in Fig. 8; Fig. 10 is a side elevation of the mechanism shown in Fig. 9; Fig. 11 is a diagrammatical view showing the operation during the process of grinding the teeth and illustrating the extreme points of movement of the grinder.

In all the views, like parts are designated by the same reference characters.

The machine comprises a base 1, which is hollow, preferably of cast iron. This base has a cylindrical extension 2, within which is mounted the reciprocating support 3, which carries the wheel to be ground, and which is reciprocated up and down during the grinding operation. The frame has an extension 4 (see Fig. 5) which is closed by a man-hole cover 5. The main shaft 6 is horizontal, and is carried in bearings within

the frame 1. One of these bearings 7 is carried in a removable plate so that the shaft can be taken out and put in. The shaft is rotated by means of a spur gear 8, which engages with a pinion 9 carried on a counter-shaft 10, a pulley 11 is mounted on the hub of the pinion 9 and rotates the pinion, gear and shaft 6. The shaft 6 is provided with a crank 12, to which is connected a pitman 13, and this pitman is connected by means of a pin 14, to the support 3, and serves to reciprocate it in a vertical direction. The support 3 is hollow, as shown.

In the extension 4 of the frame 1, are two vertical shafts 15 and 16. The shaft 15 is mounted in a bearing 17 on the support 3, and a bearing 18 at the top of the extension 4. The shaft 16 is mounted in bearings 19 and 20 in the bottom and top of the extension 4. The shaft 15 is rotated by means of the shaft 6 through the agency of a worm 21, and worm wheel 22, the first being carried by the shaft 6 and the second by the shaft 15. The proportion of reduction may be varied as occasions require, the illustration showing it to be a reduction of about 1 in 36; in other words, the shaft 15 will be rotated once to every 36 times the shaft 6 is turned. The shaft 15 is adapted to be reciprocated in time with the support 3, through the agency of the bearing 17. Collars 17^a on the shaft 15, and on each side of the bearing 17, compel the shaft to reciprocate with the bearing. The worm wheel 22 has an extended hub 22^a which enters a bearing 22^b, a collar 22^c holding it in place. The shaft 15 lies within the worm wheel and hub, and is rotated thereby by means of a feather 15^a. The shaft 15 carries a cam 23. This cam is shown in Fig. 7, to be formed in the shape of a spiral for nearly the entire circumference of the cam, the two ends of the spiral being connected together by a sharp shoulder. This cam serves to oscillate the shaft 16 through the agency of an arm 24, which carries a stud 25 which engages with the cam slot. The shaft 15 actuates the locking and indexing mechanism for holding the wheel in position while the tooth is being ground, and for advancing it the space of a tooth so as to present it in position for grinding a new tooth. The shaft 16 actuates the grinder means for moving the grinder in the proper path to grind the tooth to the proper shape and size. The 110

wheel 26 which is being ground is supported upon a table 27, having a flange upon which the wheel rests and a collar which passes through the centerbore of the wheel. This 5 table is made removable, so that another of different size may be substituted when a wheel of different size is being ground. The table 27 rests upon a rotating table 28, which also is provided with a flange and a collar, 10 the collar being inserted within the center of the collar of the preceding table. Both tables are secured together by any means such as a bolt 29. The support 3 is provided with a centrally rising pin 30 which passes 15 through the collars of both tables. The upper extremity of the pin is threaded as shown, and is provided with lock nuts 31, which upon being applied, will prevent the table 28 from rising. A dog 32 is also applied 20 to the screw threads and has depending bolts 33, which engage against the upper edge of the hub of the wheel to hold it in position after it is adjusted. A suitable ball bearing 34 is interposed between the upper 25 face of the support 3, and the lower face of the flange of the table 28, so that the table may be rotated upon the support 3 with a minimum amount of friction. A ball bearing is useful, owing to the great 30 weight of the wheel which is being ground, and the necessity of a quick movement of the wheel by the feeding and indexing mechanism, which will be described.

A depending apron 35 having an outward 35 extending lower edge, serves to collect the abraded material removed from the teeth on the wheel 26, and the water used in grinding. Inside of the apron 35 is a tubular member 36, having ratchet teeth 37 on its 40 periphery, which constitutes a portion of the feeding mechanism. Inside of this tubular member is a circular series of teeth 38, which constitutes a portion of the locking and indexing mechanism. The upper outer edge 45 of the support 3 carries a petticoat 39, whose lower edge is constantly submerged in water or other liquid contained in an annular receptacle 40, forming a portion of the frame 1. This bath acts as a seal and prevents 50 the entrance of dust or dirt into the bearing of the support 3.

The grinder heads 41 are carried upon tables 42, formed integral with the frame 1, and carry the grinders 43. The heads are 55 made hollow for lightness, and also to permit the accommodation of mechanism within them, and are preferably divided into two chambers by means of a partition as shown in Fig. 6. The heads 41 are oscillated during 60 the grinding operation, and also bodily moved around a circular surface so as to develop the proper shape of the involute tooth. In order to hold them in position, they are provided with a depending extension or stud 44, surrounded by a collar 45

which is retained in place by means of a bolt 46. This stud and collar 45 pass through a slot 47 (see Fig. 11) formed in the table 42. The table 42 is also provided with an overhanging portion 48, which engages a flange 49 forming a part of the head 41, and serves as a further means of holding a head down against the table. A suitable gib 50 with adjusting bolts 51 may be provided to take up the wear. The head is also held in proper position by means of straps 52 which are connected to the side of the table 42, which is rounded for the purpose (see Fig. 6) and cross and are connected at their other ends to the sides of the heads at 53. Two straps are shown for each head, one being above the other. Suitable devices are provided for taking up the stretch of the straps, also to adjust the position of the head and the curved surfaces. In addition to these devices, springs 54 are provided which surround pins 55. These pins are secured to the table 42 and enter suitable openings on the inner faces of the heads. The springs engage between the washers 56 held 90 in place by bolts 57, and curved face washers 58, which engage with the inner walls of the head.

The heads are provided each with a boss 59, to which is connected a rod 60, which in turn is connected to a crank 61, carried by the shaft 16. The shaft 16 being given the oscillatory movement as already described, will oscillate the two heads 41 in unison, moving one in one direction and the other in the other direction, so that the two teeth will be simultaneously cut.

The straps are for the purpose of giving the proper movement to the grinding heads. They insure that a given point in the head 105 will always come opposite a given point in the curved surface. They produce a rolling effect of the two curved surfaces one upon the other, and develop the involute shape of the tooth. If the straps were omitted, this 110 would not necessarily result. The springs hold the two surfaces always in contact. If the springs were omitted the two parts would not be held in contact and the grinder 115 would not be held against the work.

The locking and indexing mechanism as already described is actuated by means of the shaft 15. This shaft 15 has a wheel 62 at its upper extremity. The periphery of this wheel is provided with the cam slot 63, 120 of the shape shown in Fig. 10. Within this cam slot engages a finger 64, which is carried upon a pin 65, which passes through a bearing 66. The other end of the pin 65 is in the form of a finger 67. This finger is 125 adapted to engage between two of the projections 38, carried upon the table 27. The finger 67 may be formed with a sharpened point, so that it will be self-centering between the projections 38. This finger con- 130

stitutes a lock for the table and the indexing device, and is automatically drawn out and inserted in place by means of the action of the projection 64 in the cam slot 63. As shown in Fig. 10, this cam slot 63 is formed with a distortion, which distortion is in the particular position to cause the movement of the finger 67 at the particular time. The feeding mechanism is also actuated by means of the wheel 62. This wheel in addition to carrying the cam slot 63 carries a pin 68, which forms a crank. This pin projects through the upper surface of the wheel 62, and is adapted to successively engage with the teeth 37, and intermittently rotate the table 27, and with it the wheel 26. Means is provided for adjusting the position of the pin 68 so as to accommodate it for use with tables of different sizes, which are necessary for use with wheels of different sizes. The pin 68 is carried upon a support 69, which slides in ways formed in a transverse slot through the wheel 62. This support is adjusted in position by means of the screw 70, having a projecting head 71 to which the wrench may be applied.

The grinding tools 43 are each in the form of a disk of abrasive material. Means, not shown, is provided for supplying water to the grinding surface.

A very important part of the invention resides in making the grinder of such a type that it engages at its edge with the tooth being ground, in contradistinction from engagement with one face or a corner, which is the case in previous forms of machines. Among the advantages which reside in having the grinder engage at its periphery are that it can grind finer teeth, as the grinder can be thinner than one which engages with one face. Another advantage is that as the grinder wears it merely decreases in diameter and not in thickness. If it should be attempted to grind a fine pitch gear with a face engaging grinder, as the grinder wore it would become thinner, and liable to breakage.

The support for each tool is alike and consists of a shaft 72, which is mounted in bearings on a subframe 73. The shaft 72 is provided with a pulley 74, with which a hub may be engaged for rotating the shaft and grinding wheel at the proper rate of speed. The subframe 72 is supported upon the main part of the head 41 by a dovetailed joint shown in Fig. 4, and the parts are so arranged that the subframe may be moved along the head toward and away from the wheel which is being ground so as to accommodate the wear of the grinding tool and also to accommodate different sized wheels which are being ground. One means for feeding the tool against the work is shown. This consists of a bolt 75^a carried in a bearing 75^b on the head and which al-

lows the bolt to engage with the subframe in such a manner that it can be fed forward.

The operation of the machine is as follows: The wheel which is to be ground is placed upon the table 27, and surrounds the collar of such table. It is properly adjusted in relation to the teeth 38, by means of the dog 32 and bolts 33. The grinders are then adjusted properly in position, and are connected by belts so as to be rotated at the proper degree of speed. Means is formed for feeding the proper amount of water at the proper places. Power then being applied to the pulley 11, will rotate the shaft 6, the shaft 15, and give the oscillatory movement to the shaft 16. The support 3 will be reciprocated carrying with it the table 27 and the wheel 26. While the wheel is being reciprocated, the shafts 15 and 16 will be slowly rotated and oscillated. The action of the grinder is more clearly shown in Fig. 11. It starts in the full line position shown at the outer edge of the teeth and gradually works into a position on the side of the tooth, the wheel being constantly reciprocated so that every portion of the surface of that side of the tooth will be acted upon by the grinder.

Owing to the manner of mounting the heads, and connecting them to the curved surface of the table 42, by the bands or strips 52, the grinding edge of the grinder will describe a path of a true involute. When the grinder has reached the base of the tooth the shaft 15 will have made nearly a complete revolution. The pin 25 engaging with the cam 23 will at this time enter the distorted portion of the cam slot, and quickly reverse the movement of the arm 24 and shaft 16. This will cause a quick return motion to the heads 41—41. While this is occurring a finger 64 will be entering the distorted portion of the cam slot 63, and will disengage the finger 67 from the teeth 38. At the same moment the pin 68 will engage with one of the teeth 37, and give the table 27 a partial rotation sufficient to present a new tooth to the action of the grinding tool. The finger 67 will then enter the slot in the table and index the wheel. The action will then be repeated.

As shown in the drawings, two grinding tools are employed. They attack the wheel on opposite points and simultaneously operate. Therefore after the wheel has made one-half a revolution, one face of all the teeth will have been ground. The wheel may then be removed, reversed and returned to position, and the other faces of the teeth ground.

The machine, it will be seen, operates by grinding the face of the teeth from the outside toward the inside. This is an important improvement especially when the machine is applied to the grinding of wheels of excessively hard material. Such wheels

are usually cast and imperfections are formed in the casting. In machines in which the tooth is ground by the tool traveling from inward outwardly, the tool is first positioned by being brought in close contact to the surface to be ground. If there are any imperfections in the casting, the grinding tool will strike these during the quick motion necessary in order to bring it into position. This will result in damaging or destroying the grinding tool.

According to the present invention, the grinding being done from the outside towards the center, and the tool being slowly fed in at the rate necessary to secure the proper abrasive action, if the tool comes into contact with any imperfections it will slowly grind them down without being injured.

20. Another great advantage incident to the present invention is the possibility of avoiding the use of a master wheel, the development of the involute being made directly by the rocking movement of the grinder head 25 upon the curved surface. The use of a master causes error in a number of directions: (1) As is well understood, in cutting wheels such as are used for masters, there are not as many cutters employed as there are sizes 30 of tooth, consequently one cutter must be used for several different sizes of tooth, and will not accurately cut in but one size. (2) There is error in the master caused by the cutting operation, so that it is not exactly like the cutter. (3), There is error in the transfer mechanism between the tracing finger and the grinder, which may magnify or decrease the errors in the master, or make new errors; and (4), there are errors in the 40 movement of the grinder in engagement with the wheel, and which is being ground.

By my present invention, I avoid these errors, and make it possible to accurately grind teeth of all sizes, as it is not necessary 45 to have a master or other form to develop the shape of the tooth.

The improvements herein disclosed are not limited to the machine illustrated, as they may be used in connection with other 50 forms of machines. One form of machine which they may use in connection with this is that disclosed in a joint application for patent filed by myself and Charles G. Atha, filed May 16, 1905, Serial No. 260,617.

55 Having now described my invention, what I claim as new and desire to secure by Letters Patent, is:

1. In a machine for grinding the teeth of gear wheels, the combination with means for supporting a wheel, of a grinder, and means for engaging the edge of the grinder on the line of the spur tooth, and between the teeth of the wheel.

2. In a machine for grinding the teeth of 65 gear wheels, the combination with means for

supporting a wheel, of a grinder, means for engaging the edge of the grinder between the teeth of the wheel, and means for reciprocating the wheel, to cause the grinder to engage with the tooth throughout its depth.

3. In a machine for grinding the teeth of spur gear wheels, the combination with a support for the wheel, of a grinder, means for engaging the grinder with a tooth of the wheel, means for moving the grinder in a path of a true involute in engagement with the wheel on the line of a spur tooth, and means for disengaging the grinder from the wheel and returning it out of contact with the wheel.

4. In a machine for grinding the teeth of spur gear wheels, the combination with a support for the wheel, of a grinder, means for engaging the grinder with a tooth of the wheel, means for moving the grinder in a path of a true involute on the line of a spur tooth, means for disengaging the grinder from the wheel, and means for relatively moving the grinder and wheel, to place the grinder in position for grinding another tooth.

5. In a machine for grinding the teeth of gear wheels, the combination with a support for the wheel, of a grinder, a grinder head, and means for moving the grinder in the path of an involute on the line of a spur tooth, the said means comprising rocking members and means for holding the members in engagement.

6. In a machine for grinding the teeth of gear wheels, the combination with a support to the wheel, a grinder and means for moving the grinder in the path of an involute, the said means comprising a member having a curved surface, a member having a plane surface, flexible means for holding the surfaces together, and means for rocking one surface upon the other.

7. In a machine for grinding the teeth of gear wheels, the combination with means for supporting the wheel, of a grinder, a grinder head, the said grinder head engaging with a curved surface, straps for determining the proper relation of the grinder head to the curved surface, means for engaging the grinder head with the curved surface and means for rocking the grinder head to cause the grinder to describe the path of an involute.

8. In a machine for grinding the teeth of gear wheels, the combination with a support for the wheel, of a grinder and grinder head, a member having a curved surface engaging with the grinder head, straps connecting the grinder head and curved surface, elastic means for engaging the grinder head with the curved surface, and means for rolling the grinder head upon the curved surface to cause the grinder to describe the path of an involute.

9. In a machine for grinding the teeth of gear wheels, the combination of a frame with a reciprocating support therein, and a liquid seal, inclosing the support. 65
10. In a machine for grinding the teeth of gear wheels, the combination with a rotating table, a support thereon for the wheel to be ground, a set of ratchet teeth connected to the table, and by means of which it may be rotated, and a rotary member having a pin adapted to engage with the ratchet teeth and intermittently rotate the table. 70
11. In a machine for grinding the teeth of gear wheels, the combination with a support for the wheel, of a grinder adapted to engage between the teeth of the wheel with its edge, and means for feeding the grinder in relation to the wheel, as the grinder wears away. 75
12. In a machine for grinding the teeth of gear wheels, the combination with means for supporting the wheel, a shaft, a worm gear thereon, a worm wheel in engagement with the worm gear, a shaft directly rotated by the worm gear, and another shaft indirectly reciprocated by means of a cam rotated by the worm gear, and means actuated by the two shafts for operating the mechanism for grinding the wheel. 80
13. In a machine for grinding the teeth of gear wheels, the combination of a frame and reciprocating support for the wheel, a shaft and connections between the shaft and support for reciprocating the latter, a table carried by the support and adapted to rotate thereon, means carried by the table for supporting the wheel, a worm carried by the shaft, a worm wheel in engagement therewith and carrying a cam, a second shaft in engagement with the worm wheel, a third shaft having a member engaging with the cam by means of which it is reciprocated, a grinder, a grinder head, the said grinder head engaging with a fixed curved surface, and connections between the reciprocating shaft and grinder head for reciprocating it. 85
14. In a machine for grinding the teeth of gear wheels, the combination of a frame and reciprocating support for the wheel, a shaft and connections between the shaft and support for reciprocating the latter, a table carried by the support and adapted to rotate thereon, means carried by the table for supporting the wheel, a worm carried by the shaft, a worm wheel in engagement therewith and carrying a cam, a second shaft in engagement with the worm wheel, a third shaft having a member engaging with the cam by means of which it is reciprocated, a grinder, a grinder head, the said grinder head engaging with a fixed curved surface, connections between the reciprocating shaft and grinder head for reciprocating it, and means for feeding the grinder against the work. 90
15. In a machine for grinding the teeth of gear wheels, the combination of a frame and reciprocating support for the wheel, a shaft and connections between the shaft and support for reciprocating the latter, a table carried by the support and adapted to rotate thereon, means carried by the table for supporting the wheel, a worm carried by the shaft, a worm wheel in engagement therewith and carrying a cam, a second shaft in engagement with the worm wheel, a third shaft having a member engaging with the cam by means of which it is reciprocated, a grinder, a grinder head, the said grinder head engaging with a fixed curved surface, springs for engaging the grinder head against the curved surface, and connections between the reciprocating shaft and grinder head for reciprocating it. 95
16. In a machine for grinding the teeth of gear wheels, the combination of a frame, and reciprocating support for the wheel, a shaft and connections between the shaft and support for reciprocating the latter, a table carried by the support and adapted to rotate thereon, means carried by the table for supporting the wheel, a worm carried by the shaft, a worm wheel in engagement therewith and carrying a cam, a second shaft in engagement with the worm wheel, a third shaft having a member engaging with the cam by means of which it is reciprocated, a grinder, a grinder head, the said grinder head engaging with a fixed curved surface, springs for engaging the grinder head against the curved surface, and connections between the reciprocating shaft and grinder head for reciprocating it. 100
17. In a machine for grinding the teeth of gear wheels, the combination of a frame and reciprocating support for the wheel, a shaft and connections between the shaft and support for reciprocating the latter, a table carried by the support and adapted to rotate thereon, means carried by the table for supporting the wheel, a worm carried by the shaft, a worm wheel in engagement therewith and carrying a cam, a second shaft in engagement with the worm wheel, a third shaft having a member engaging with the cam by means of which it is reciprocated, a grinder, a grinder head, the said grinder head engaging with a fixed curved surface, straps connecting the grinder head and curved surface, springs for engaging the grinder head against the curved surface, connections between the reciprocating shaft and grinder head for reciprocating it, and means for feeding the grinder against the work. 105
18. In a machine for grinding the teeth of gear wheels, the combination of a frame and

reciprocating support for the wheel, a shaft and connections between the shaft and support for reciprocating the latter, a table carried by the support and adapted to rotate thereon, and a series of indexing teeth thereon, a cam carried by the second rotating shaft, a finger engaging with the cam, and adapted to engage between the indexing teeth carried by the rotating table, means 5 carried by the table for supporting the wheel, a worm carried by the shaft, a worm wheel in engagement therewith and carrying a cam, a second shaft in engagement with the worm wheel, but free to slide 10 lengthwise therein, means carried by the support for reciprocating the shaft in time therewith, a third shaft having a member engaging with the cam by which it is reciprocated, a grinder, a grinder head, the said 15 grinder head engaging with a fixed curved surface, straps connecting the grinder head and curved surface, springs for engaging the grinder head against the curved surface, connections between the reciprocating shaft and 20 grinder head for reciprocating it, and means for feeding the grinder against the work.

19. In a machine for grinding the teeth of gear wheels, the combination of a frame and 30 reciprocating support for the wheel, a shaft and connections between the shaft and support for reciprocating the latter, a table carried by the support and adapted to rotate thereon, ratchet teeth on the table, means 35 carried by the table for supporting the wheel, a worm carried by the shaft, a worm wheel in engagement therewith and carrying a cam, a second shaft in engagement with the worm wheel, a third shaft having a member 40 engaging with the cam by means of which it is reciprocated, a crank rotated by the shaft and adapted to successively engage with the ratchet teeth on the table, a grinder, a grinder head, the said grinder head engaging 45 with a fixed curved surface, and connections between the reciprocating shaft and grinder head for reciprocating it.

20. In a machine for grinding the teeth of gear wheels, the combination of a frame and 50 reciprocating support for the wheel, a shaft and connections between the shaft and support for reciprocating the latter, a table carried by the support and adapted to rotate thereon, ratchet teeth on the table, a grinder, 55 a grinder head, the said grinder head engaging with a fixed curved surface, connections between the reciprocating shaft and grinder head for reciprocating it, and means for feeding the grinder against the work, a crank 60 rotated by the second shaft and adapted to successively engage with the ratchet teeth on the table, means carried by the table for supporting the wheel, a worm carried by the shaft, a worm wheel in engagement there- 65 with and carrying a cam, a second shaft in

engagement with the worm wheel, and a third shaft having a member engaging with the cam by means of which it is reciprocated.

21. In a machine for grinding the teeth of gear wheels, the combination of a frame and 70 reciprocating support for the wheel, a shaft and connections between the shaft and support for reciprocating the latter, a table carried by the support and adapted to rotate thereon, ratchet teeth on the table, means 75 carried by the table for supporting the wheel, a worm carried by the shaft, a worm wheel in engagement therewith and carrying a cam, a second shaft in engagement with the worm wheel, a third shaft having a member 80 engaging with the cam by means of which it is reciprocated; a grinder, a grinder head, the said grinder head engaging with a fixed curved surface, springs for engaging the grinder head against the curved surface, connections between the reciprocating shaft and grinder head for reciprocating it, a crank 85 rotated by the second shaft and adapted to successively engage with the ratchet teeth on the table.

22. In a machine for grinding the teeth of gear wheels, the combination of a frame and reciprocating support for the wheel, a shaft and connections between the shaft and support for reciprocating the latter, a table carried by the support and adapted to rotate thereon, ratchet teeth on the table, means 90 carried by the table for supporting the wheel, a worm carried by the shaft, a worm wheel in engagement therewith and carrying a cam, a second shaft in engagement with the worm wheel, a third shaft having a member 95 engaging with the cam by means of which it is reciprocated, a crank rotated by the second shaft and adapted to successively engage with the ratchet teeth on the table, a grinder, a grinder head, the said grinder head engaging 100 with a fixed curved surface, straps connecting the grinder head and curved surface, and connections between the reciprocating 105 shaft and grinder head for reciprocating it.

23. In a machine for grinding the teeth of gear wheels, the combination of a frame and reciprocating support for the wheel, a shaft and connections between the shaft and support for reciprocating the latter, a table carried by the support and adapted to rotate thereon, ratchet teeth on the table, means carried by the table for supporting the wheel, a worm carried by 115 the shaft, a worm wheel in engagement therewith and carrying a cam, a second shaft in engagement with the worm wheel, a third shaft having a member 120 engaging with the cam by means of which it is reciprocated, a crank rotated by the second shaft and adapted to successively engage with the ratchet teeth on the table, a grinder, a grinder head, the said grinder head engaging 125 with a fixed curved surface, straps connect- 130

ing the grinder head and curved surface, connections between the reciprocating shaft and grinder head for reciprocating it, and means for feeding the grinder against the 5 work.

24. In a machine for grinding the teeth of gear wheels, the combination of a frame and reciprocating support for the wheel, a shaft and connections between the shaft and support for reciprocating the latter, a table carried by the support and adapted to rotate thereon, means carried by the table for supporting the wheel, a worm carried by the shaft, a worm wheel in engagement therewith and carrying a cam, a second shaft in engagement with the worm wheel, but free to slide lengthwise therein, means carried by the support for reciprocating the shaft in time therewith, a third shaft having a member engaging with the cam by means of which it is reciprocated, a grinder, a grinder head, the said grinder head engaging with a fixed curved surface, and connections between the reciprocating shaft and grinder head for reciprocating it.

25. In a machine for grinding the teeth of gear wheels, the combination of a frame and reciprocating support for the wheel, a shaft and connections between the shaft and support for reciprocating the latter, a table carried by the support and adapted to rotate thereon, means carried by the table for supporting the wheel, a worm carried by the shaft, a worm wheel in engagement therewith and carrying a cam, a second shaft in engagement with the worm wheel, but free to slide lengthwise therein, means carried by the support for reciprocating the shaft in time therewith, a third shaft having a member engaging with the cam by means of which it is reciprocated, a grinder, a grinder head, the said grinder head engaging with a fixed curved surface, and connections between the reciprocating shaft and grinder head for reciprocating it, and means for feeding the grinder against the work.

26. In a machine for grinding the teeth of gear wheels, the combination of a frame and reciprocating support for the wheel, a shaft and connections between the shaft and support for reciprocating the latter, a table carried by the support and adapted to rotate thereon, means carried by the table for supporting the wheel, a worm carried by the shaft, a worm wheel in engagement therewith and carrying a cam, a second shaft in engagement with the worm wheel, but free to slide lengthwise therein, means carried by the support for reciprocating the shaft in time therewith, a third shaft being a member engaging with the cam by means of which it is reciprocated, a grinder, a grinder head, the said grinder head engaging with a fixed curved surface, springs for engaging 65 the grinder head against the curved sur-

face, and connections between the reciprocating shaft and grinder head for reciprocating it.

27. In a machine for grinding the teeth of gear wheels, the combination of a frame and reciprocating support for the wheel, a shaft and connections between the shaft and support for reciprocating the latter, a table carried by the support and adapted to rotate thereon, means carried by the table or supporting the wheel, a worm carried by the shaft, a worm wheel in engagement therewith and carrying a cam, a second shaft in engagement with the worm wheel, but free to slide lengthwise therein, means carried by the support for reciprocating the shaft in time therewith, a third shaft having a member engaging with the cam by means of which it is reciprocated, a grinder, a grinder head, the said grinder head engaging with a fixed curved surface, springs for engaging the grinder head against the curved surface, connections between the reciprocating shaft and grinder head for reciprocating it, and means for feeding the grinder against the work.

28. In a machine for grinding the teeth of gear wheels, the combination of a frame and reciprocating support for the wheel, a shaft and connections between the shaft and support for reciprocating the latter, a table carried by the support and adapted to rotate thereon and a series of indexing teeth thereon, means carried by the table for supporting the wheel, a worm carried by the shaft, a worm wheel in engagement therewith and carrying a cam, a second shaft in engagement with the worm wheel, a cam carried by the second rotating shaft, a finger engaging with the cam, and adapted to engage between the indexing teeth carried by the rotating table, a third shaft having a member engaging with the cam by means of which it is reciprocated, a grinder, a grinder head, the said grinder head engaging with a fixed curved surface, and connections between the reciprocating shaft and grinder head for reciprocating it.

29. In a machine for grinding the teeth of gear wheels, the combination of a frame and reciprocating support for the wheel, a shaft and connections between the shaft and support for reciprocating the latter, a table carried by the support and adapted to rotate thereon, and a series of indexing teeth thereon, means carried by the table for supporting the wheel, a worm carried by the shaft, a worm wheel in engagement therewith and carrying a cam, a second shaft in engagement with the worm wheel, a cam carried by the second rotating shaft, a finger engaging with the cam, and adapted to engage between the indexing teeth carried by the rotating table, a third shaft having a member engaging with the cam by means of which 130

it is reciprocated, a grinder, a grinder head, the said grinder head engaging with a fixed curved surface, connections between the reciprocating shaft, and grinder head for reciprocating it, and means for feeding the grinder against the work.

30. In a machine for grinding the teeth of gear wheels, the combination of a frame and reciprocating support for the wheel, a shaft and connections between the shaft and support for reciprocating the latter, a table carried by the support and adapted to rotate thereon, and a series of indexing teeth thereon, means carried by the table for supporting the wheel, a worm carried by the shaft, a worm wheel in engagement therewith and carrying a cam, a second shaft in engagement with the worm wheel, a cam carried by the second rotating shaft, a finger engaging with the cam, and adapted to engage between the indexing teeth carried by the rotating table, a third shaft having a member engaging with the cam by means of which it is reciprocated, a grinder, a grinder head, the said grinder head engaging with a fixed curved surface, straps connecting the grinder head and curved surface, connections between the reciprocating shaft and grinder head for reciprocating it, and means for feeding the grinder against the work.

31. In a machine for grinding the teeth of gear wheels, the combination of a frame and reciprocating support for the wheel, a shaft and connections between the shaft and support for reciprocating the latter, a table carried by the support and adapted to rotate thereon, and a series of indexing teeth thereon, means carried by the table for supporting the wheel, a worm carried by the shaft, a worm wheel in engagement therewith and carrying a cam, a second shaft in engagement with the worm wheel, a cam carried by the second rotating shaft, a finger engaging with the cam, and adapted to engage between the indexing teeth carried by the rotating table, a third shaft having a member engaging with the cam by means of which it is reciprocated, a crank rotated by the second shaft and adapted to successively engage with the ratchet teeth on the table, and a series of indexing teeth thereon, a cam carried by the second rotating shaft, a finger engaging with the cam, and adapted to engage between the indexing teeth carried by the rotating table, a grinder, a grinder head, the said grinder head engaging with a fixed curved surface, straps connecting the grinder head and curved surface, connections between the reciprocating shaft and grinder head for reciprocating it, and means for feeding the grinder against the work.

32. In a machine for grinding the teeth of gear wheels, the combination of a frame and reciprocating support for the wheel, a shaft and connections between the shaft and support for reciprocating the latter, a table carried by the support and adapted to rotate thereon, and a series of indexing teeth there-

on, means carried by the table for supporting the wheel, a worm carried by the shaft, a worm wheel in engagement therewith and carrying a cam, a second shaft in engagement with the worm wheel, a cam carried by the second rotating shaft, a finger engaging with the cam, and adapted to engage between the indexing teeth carried by the rotating table, a third shaft having a member engaging with the cam by means of which it is reciprocated, a grinder, a grinder head, the said grinder head engaging with a fixed curved surface, straps connecting the grinder head and curved surface, connections between the reciprocating shaft and grinder head for reciprocating it, and means for feeding the grinder against the work.

33. In a machine for grinding the teeth of gear wheels, the combination of a frame and reciprocating support for the wheel, a shaft and connections between the shaft and support for reciprocating the latter, a table carried by the support and adapted to rotate thereon, ratchet teeth on the table, means carried by the table for supporting the wheel, a worm carried by the shaft, a worm wheel in engagement therewith and carrying a cam, a second shaft in engagement with the worm wheel, a third shaft having a member engaging with the cam by means of which it is reciprocated, a crank rotated by the second shaft and adapted to successively engage with the ratchet teeth on the table, and a series of indexing teeth thereon, a cam carried by the second rotating shaft, a finger engaging with the cam, and adapted to engage between the indexing teeth carried by the rotating table, a grinder, a grinder head, the said grinder head engaging with a fixed curved surface, straps connecting the grinder head and curved surface, connections between the reciprocating shaft and grinder head for reciprocating it, and means for feeding the grinder against the work.

34. In a machine for grinding the teeth of gear wheels, the combination of a frame and reciprocating support for the wheel, a shaft and connections between the shaft and support for reciprocating the latter, a table carried by the support and adapted to rotate thereon, ratchet teeth on the table, means carried by the table for supporting the wheel, a worm carried by the shaft, a worm wheel in engagement therewith and carrying a cam, a second shaft in engagement with the worm wheel, a third shaft having a member engaging with the cam by means of which it is reciprocated, a crank rotated by the second shaft and adapted to successively engage with the ratchet teeth on the table, and a series of indexing teeth thereon, a cam carried by the second rotating shaft, a finger engaging with the cam, and adapted to engage between the indexing teeth carried by the rotating table, a grinder, a grinder head, the

said grinder head engaging with a fixed curved surface, straps connecting the grinder head and curved surface, springs for engaging the grinder head against the curved surface, connections between the reciprocating shaft and grinder head for reciprocating it, and means for feeding the grinder against the work.

35. In a machine for grinding the teeth of gear wheels, the combination of a frame and reciprocating support for the wheel, a shaft and connections between the shaft and support for reciprocating the latter, a table carried by the support and adapted to rotate thereon, ratchet teeth on the table, means carried by the table for supporting the wheel, a worm carried by the shaft, a worm wheel in engagement therewith and carrying a cam, a second shaft in engagement with 20 worm wheel, but free to slide lengthwise therewith, means carried by the support for reciprocating the shaft in time therewith, a third shaft having a member engaging with the cam by means of which it is reciprocated, a crank 25 rotated by the second shaft and adapted to successively engage with the ratchet teeth on the table, and a series of indexing teeth thereon, a cam carried by the second rotating shaft, a finger engaging with the cam, 30 and adapted to engage between the indexing teeth carried by the rotating table, a grinder, a grinder head, engaging with a fixed surface, straps connecting the grinder head and curved surface, springs for engaging the 35 grinder head against the curved surface, connections between the reciprocating shaft and grinder head for reciprocating it, and means for feeding the grinder against the work.

36. In a machine for grinding the teeth of
40 gear wheels, the combination of a frame and
reciprocating support for the wheel, a shaft
and connections between the shaft and sup-
port for reciprocating the latter, a table car-
ried by the support and adapted to rotate
45 thereon, ratchet teeth on the table, means
carried by the table for supporting the wheel,
a worm carried by the shaft, a worm wheel
in engagament therewith and carrying a
cam, a second shaft in engagement with the
50 worm wheel, but free to slide lengthwise
therein, means carried by the support for re-
ciprocating the shaft in time therewith, a
third shaft having a member engaging with
the cam by means of which it is reciprocated,
55 a crank rotated by the second shaft and
adapted to successively engage with the
ratchet teeth on the table, and a series of in-
dexing teeth thereon, a cam carried by the
second rotating shaft, a finger engaging with
60 the cam, and adapted to engage between the
indexing teeth carried by the rotating table,
a grinder, a grinder head, the said grinder
head engaging with a fixed curved surface,
straps connecting the grinder head and
65 curved surface, springs for engaging the

grinder head against the curved surface and connections between the reciprocating shaft and grinder head for reciprocating it.

37. In a machine for grinding the teeth of gear wheels, the combination of a frame and reciprocating support for the wheel, a shaft and connections between the shaft and support for reciprocating the latter, a table carried by the support and adapted to rotate thereon, ratchet teeth on the table, means carried by the table for supporting the wheel, a worm carried by the shaft, a worm wheel in engagement therewith and carrying a cam, a second shaft in engagement with the worm wheel, but free to slide lengthwise therein, means carried by the support for reciprocating the shaft in time therewith, a crank rotated by the second shaft, and adapted to successively engage with the ratchet teeth on the table, a third shaft having a member engaging with the cam by means of which it is reciprocated, a grinder, a grinder head, the said grinder head engaging with a fixed curved surface, straps connecting the grinder head and curved surface, springs for engaging the grinder head against the curved surface, connections between the reciprocating shaft and grinder head for reciprocating it, and means for feeding the grinder against the work. 70 75 80 85 90 95

38. In a machine for grinding the teeth of gear wheels, the combination of a frame and reciprocating support for the wheel, a shaft and connections between the shaft and support for reciprocating the latter, a table carried by the support and adapted to rotate thereon, ratchet teeth on the table, means carried by the table for supporting the wheel, a worm carried by the shaft, a worm wheel in engagement therewith and carrying a cam, a second shaft in engagement with the worm wheel, but free to slide lengthwise, means carried by the support for reciprocating the shaft in time therewith, a third shaft having a member engaging with the cam by means of which it is reciprocated, a crank rotated by the second shaft and adapted to successively engage with the ratchet teeth on the table, and a series of indexing teeth thereon, a cam carried by the second rotating shaft, a finger engaging with the cam, and adapted to engage between the indexing teeth carried by the rotating table, a grinder, a grinder head, the said grinder head engaging with a fixed curved surface, springs for engaging the grinder head against the curved surface, connections between the reciprocating shaft and grinder head for reciprocating it, and means for feeding the grinder against the work.

39. In a machine for grinding the teeth of gear wheels, the combination of a frame and reciprocating support for the wheel, a shaft and connections between the shaft and sup- 130

port for reciprocating the latter, a table carried by the support and adapted to rotate thereon, ratchet teeth on the table, means carried by the table for supporting the 5 wheel, a worm carried by the shaft, a worm wheel in engagement therewith and carrying a cam, a second shaft in engagement with the worm wheel, but free to slide lengthwise therein, means carried by the support 10 for reciprocating the shaft in time therewith, a third shaft having a member engaging with the cam by means of which it is reciprocated, a crank rotated by the second shaft and adapted to successively engage 15 with the ratchet teeth on the table, and a series of indexing teeth thereon, a cam carried by the second rotating shaft, a finger engaging with the cam, and adapted to engage between the indexing teeth carried by the rotating table, 20 the rotating table, a grinder, a grinder head, the said grinder head engaging with a fixed curved surface, springs for engaging the grinder head against the curved surface, connections between the reciprocating shaft 25 and grinder head for reciprocating it, and means for feeding the grinder against the work.

40. In a machine for grinding the teeth of gear wheels, the combination of a frame and reciprocating support for the wheel, a shaft 30 and connections between the shaft and support for reciprocating the latter, a table carried by the support and adapted to rotate

thereon, ratchet teeth on the table, means carried by the table for supporting the 35 wheel, a worm carried by the shaft, a worm wheel in engagement therewith and carrying a cam, a second shaft in engagement with the worm wheel, but free to slide lengthwise therein, means carried by the support for 40 reciprocating the shaft in time therewith, a third shaft having a member engaging with the cam by means of which it is reciprocated, a crank rotated by the second shaft and adapted to successively engage with the 45 ratchet teeth on the table, and a series of indexing teeth thereon, a cam carried by the second rotating shaft, a finger engaging with the cam, and adapted to engage between the indexing teeth carried by the rotating table, 50 a grinder, a grinder head, the said grinder head engaging with a fixed curved surface, straps connecting the grinder head and curved surface, springs for engaging the grinder head against the curved surface, 55 connections between the reciprocating shaft and grinder head for reciprocating it, and means for feeding the grinder against the work.

This specification signed and witnessed 60 this second day of May, 1906.

FREDERICK A. PHELPS.
